UNITED STATES PATENT OFFICE.

ALEXIS KOBINE, OF LONDON, ENGLAND, ASSIGNOR TO ROBERT BOBY LIMITED, OF BURY ST. EDMUNDS, ENGLAND, A BRITISH COMPANY.

HACKLING MACHINE.

Application filed December 20, 1928, Serial No. 327,357, and in Great Britain July 18, 1927.

This invention relates to machines for hackling flax, hemp, jute and analogous fibres, such machines being of the kind in which the stricks of fibrous material to be hackled 5 are exposed to the action of pins or combs carried by endless revolving or travelling sheets operating on both sides of each strick. In such machines as usually constructed the operative part of the travel of the pins 10 is that in which they are moving downward; the stricks are gripped by holders which are caused to rise and fall between the sheets, and in the falling movement the material accompanies the pins on the sheets 15 moving in the same direction, and the pins penetrate the material without hackling it; the holders then pause for a few seconds during which the pins hackle the material; then the holders rise, dragging the already hackled 20 material upwards against the downwardly moving pins. Thus instead of the gradual penetration which takes place in the process of hackling by hand labour, the pins or combs in these machines as usually arranged abruptly 25 penetrate the fibrous material while it is falling, the speed of hackling then varying as the holders rise and fall or remain stationary before the period of reversal of their stroke, and consequently different portions 30 of the same strick receive treatment of varying intensity, which is in some cases too severe and causes breakage of the fibres. It has been proposed, however, to carry the stricks through the machine in a substantial- 35 ly horizontal direction without vertical reciprocation, and to impart to the operative surfaces of the hackle sheets movements to and from each other both at their upper and lower ends, the bottom rollers first approach- 40 ing each other, then the top rollers so that the action of the sheets extends progressively up the strick, then the bottom rollers recede from each other, and finally the top rollers recede to release the strick; thus the 45 active portion of the sheet travels in a straight line throughout the hackling process.

The purpose of this invention is to enable a hackling machine to act on the material in 50 a manner more nearly resembling the manner in which it is treated in hackling by hand labour.

According to the invention means are pro- 55 vided to vary the distances between the ends of the pins of the revolving or endless travel-

ling sheets on opposite sides of the strick and therefore their action on the material at all parts of the length of the strick during the hackling process, by causing portions of the sheets intermediate between the upper and lower rollers to be protruded beyond 60 their normal paths, so that the said portions of opposite sheets approach each other at the beginning of the cycle of operations in order to engage the strick. This protrusion may 65 be effected by tangential or radial arms or cam actuated mechanisms arranged to engage the inner surfaces of the sheets at the beginning of the cycle of operations, without moving the lower rollers. In order to com- 70 pensate for the increase in the periphery of the sheet involved by this protrusion towards the opposite sheet, and also to widen the gap between the upper parts of the two sheets at the time the gap between their interme- 75 diate parts is thus narrowed, the upper rollers are arranged to move in inclined guides and are supported by springs.

In order that the said invention may be clearly understood and readily carried into 80 effect, the same will now be described more fully with reference to the accompanying drawings, in which:—

Figure 1 represents in front elevation a machine embodying this invention. 85

Figure 2 is an end elevation of the gearing of the said machine taken from the left hand side, viewing Figure 1.

Figure 3 is an end elevation of the gearing of the said machine taken from the right 90 hand side, viewing Figure 1.

Figure 4 represents a transverse section taken on the line 4—4 in Figure 1, looking in the direction indicated by the arrows adjacent to the said line, with the operative 95 parts in the position they occupy at the beginning of the cycle of operations.

Figure 5 is a view similar to Figure 4 but with the operative parts in the positions they occupy at an intermediate phase in the cycle 100 of operations.

The stricks are carried on an intermittently moving gripping belt or chain, the movements of which are co-ordinated with those of the mechanism for varying the action of the pins 105 on the strick.

As one end of each strick is gripped by the chain while the exposed parts are being hackled, it is necessary in order to complete the hackling process to reverse the hold of 110

the chain on the strick, so that the end of the strick that was formerly held by the chain out of the field of action shall hang freely to be hackled in a second operation. The manner 5 in which it is considered preferable to accomplish such repeated treatment of the stricks is that frequently used in analogous machines, namely, to employ two counterpart machines connected in tandem to be driven at 10 the same speed, two endless gripping chains being employed, that is, one for each machine, and the arrangement of the said chains being such that when the first chain releases a strick the second chain grips the opposite 15 end of the strick and allows its untreated portion to hang down freely. The machine illustrated in Figure 1 may be taken to be the second machine, and portions of the chain of the first machine are seen at the right hand 20 end of Figure 1. The first machine would be similar to the second machine, except that its frame or bed would be made higher to cause the operative parts of the first machine to stand at a higher level, say about six inches 25 higher than those of the second machine. The chains employed may be of the type described in the specification of Patent No. 1,589,732.

A indicates the frame of the machine generally, B the main shaft of the machine which 30 is caused to rotate by power from any convenient source. The main shaft of the first machine, which is in the same vertical plane but at a higher level, is suitably geared to the shaft B so that the two machines operate in unison. This shaft B drives one of the travelling endless sheets directly and is operatively connected by suitable gearing with 35 a countershaft C which drives the other of such sheets. It is immaterial as to which 40 sheet is driven directly, but both sheets must be caused to travel at the same speed. Through gear trains diagrammatically illustrated in Figure 2 the shafts B, C drive intermediate shafts D, E; the shaft D transmits 45 rotation to a cam shaft or stud F, and the shaft E transmits rotation to a cam shaft or stud G. Each of the shafts D and E carries a series of tangential arms H of adjustable length, on the free ends of which arms are 50 rollers h¹ engaging the inner surfaces of the travelling sheets J, K in the position seen in Figure 4. The cam shafts F and G control the positions of the top carrier pulleys M, N of the sheets, and the shaft F actuates a 55 weighting motion hereinafter described, while the cam shaft G controls the intermittent movements of the gripping chain P. A rubber or other belt R enters the channel of the chain P and is caused by frictional contact with the said chain to travel along with 60 it. The chain P passes over pulleys p¹, p² one of which is driven intermittently while the other rotates freely. The belt R passes over freely rotating pulleys r¹, r², r³, r⁴, r⁵, r⁶. 65 Portions of the chain S and belt T of the first

machine are seen at the right hand side of Figure 1. The machine is provided with the usual rotary brushes for removing tow from the sheets J, K, needle drums or doffers for stripping the brushes, and angle beaters on 70 oscillating bars worked by eccentrics or other suitable means to strip the doffers, these parts, which are well known and need not be further described, being driven by suitable gearing from one of the shafts. The sheets J, K are 75 similar to those usually employed in hacking machines; the sheet J comprises belts represented at j¹, j², j³ in Figure 1, these belts being perforated with holes j⁴ in which engage teeth j⁵ on sprocket wheels j⁶ on the 80 shaft B, and the sheet K is similarly driven from the shaft C. Longitudinal bars j⁷, k¹ (Figures 4 and 5) secured to these belts carry the hackles; these bars and hackles (except as regards one bar) are omitted for the sake 85 of clearness in Figure 1.

The carrier pulleys M, N are mounted on shafts m¹, n¹ which are supported at their ends in blocks m², n² adapted to slide in inclined guides m³, n³ on the machine frame. 90 Springs m⁴, n⁴ tend to draw the blocks, and with them the pulleys, into the positions indicated in Figure 4, but cams f¹, g¹ on the shafts F and G respectively acting against these springs press the blocks and the pulleys M, N towards each other at a later period in the cycle of operations (see Figure 5), when the opposing surfaces of the sheets J, K are straightened out between the sprocket wheels and the carrier pulleys. Devices for regulating the tension of the sheets passing around the carrier pulleys are represented at m⁵ and n⁵.

Beside the cam g¹, a larger cam g² is secured on the shaft G (see Figure 3), this cam g² being adapted to rock an arm g³ pivoted on a shaft g⁴ in the machine frame, this arm carrying a pawl g⁵ engaging a ratchet wheel g⁶ rotatable on the same shaft g⁴, and on the said shaft and rotating with the said ratchet wheel 110 in an intermittent manner is a bevel wheel g⁷, in gear with a bevel wheel g⁸ mounted on a shaft g⁹ which carries the pulley p² and by the consequent intermittent rotation of the pulley p² a movement or travel of the chain P is effected. The shaft g⁹ also carries a sprocket wheel (not shown) which by means of a chain transmits rotation to another sprocket wheel (also not shown) and pulley S¹ whereby chain S is caused to travel. 115

Beside the cam f¹ a sprocket wheel f² is secured on a shaft F (see Figure 3) which by means of a chain f³ drives a sprocket wheel f⁴ on a shaft f⁵ on which latter is also mounted a small cam f⁶. A bent bar W is pivoted at w¹ in bearings on the machine frame, and is provided with a bowl or roller w² adapted to be engaged by the nose of the cam f⁶ to lift the bar W. This bar rests on the chain P while hacking is going on and increases the grip 125 130

of the chain on the strick. At the moment when the pins on the sheets J, K disengage the fibre, the cam f^6 lifts the bar W off the chain, when the next forward movement of the 5 chain ensues. Some power is exerted in lifting the bar, but the motion of the chain and belt absorbs much less power than the hackling operation, so that the load on the driving mechanism is equalized by this weighting motion or regulator.

When the stricks which have been hackled for a part (say two-thirds) of their length in the similarly operating first machine arrive on the chain S at the pulley s^1 , their 10 hackled ends which hang from the back of the belt T become gripped between the chain P and belt R. The ends which are gripped between chain S and belt T, not yet hackled, become released at the same time, fall, and 15 hang freely in front of belt R to be hackled by the second machine. The chain P carries the stricks through the central slot a^1 of the machine step by step, say several inches at 20 each revolution of the cam g^2 , with intervening 25 pauses, until after passing the pulleys p^1 , p^2 , the paths of the belt and chain diverge, releasing the hackled fibre, which is removed from the machine in any convenient manner. In their passage through the machine each 30 exposed part of the strick is repeatedly hackled, the cycle of operations being as follows:—The cams f^1 , g^1 and rollers h^1 being in the positions seen in Figure 4, and the bar W in the position seen in Figure 3, the chain P 35 is stationary, the sheets J, K in the descending parts of their paths first come into contact with the strick between the two rollers h^1 , the top pulleys M, N being drawn apart by their springs m^4 , n^4 and also slightly lowered to 40 compensate for the increase in the dimensions of the sheets between their descending and ascending sides enforced by the outward pressure of the rollers h^1 , the inclined arrangement of the guides of the top pulley 45 shafts permitting this compound receding and descending movement of the said pulleys. As the shafts turn in the directions indicated by arrows in Figure 4, the rollers h^1 go out of 50 contact with the sheets, and the cams f^1 , g^1 cause the pulleys M, N to pass up their inclined guides and approach each other as seen in Figure 5. When the orbital movement of the rollers h^1 approaches completion, the 55 cams f^1 , g^1 allow the pulleys M, N to recede to disengage the strick, the cam f^6 lifts up the bar W, and the cam g^2 sets the chain P in motion to move the stricks into the next position to be again hackled preferably by finer and 60 more closely set pins. When this cam g^2 goes out of action, the position represented in Figure 4 is restored and another cycle can begin.

A portion of the outer surface of each sheet is preferably left blank or free from pins, as a safeguard against accidental engagement of the stricks at the time when it is necessary 65 for the stricks to move forward, the blank portions of the respective sheets being indicated at j^8 and k^8 in Figures 4 and 5, but this blank portion is not essential and is not claimed as a feature of this invention. 70

The tangential arms H on the shafts D, E may be replaced by radial arms, or by cam actuated mechanism.

What I claim and desire to secure by Letters Patent of the United States is:—

1. In a hackling machine of the type described, having oppositely arranged endless sheets travelling between upper and lower rollers and carrying pins adapted to operate on opposite sides of a strick supported by 80 gripping mechanism arranged to travel in a horizontal direction between said sheets, means for varying the action of said pins on said strick during the period of their operation thereon, said means comprising mechanism 85 adapted to intermittently force portions of said sheets intermediate the upper and lower rollers out of their normal paths and toward one another, whereby said portions of the opposite sheets are caused to approach one 90 another at the beginning of their period of operation on said strick.

2. Apparatus according to claim 1 wherein in the mechanism for intermittently forcing the sheets out of their normal paths comprises 95 rotatable members operatively connected to the lower rollers.

3. Apparatus according to claim 1 wherein the mechanism for intermittently forcing the sheets out of their normal paths comprises 100 rotatable members adapted to engage the inner surfaces of the sheets and force portions of them toward one another.

4. Apparatus according to claim 1, characterized by the provision of upper rollers 105 arranged in inclined guides, said rollers being adapted to recede in said guides to compensate for the protrusion of the sheets out of their normal paths.

5. Apparatus according to claim 1 characterized by the provision of upper rollers arranged in inclined guides, springs for drawing said rollers inwardly in said guides to compensate for the protrusion of the sheets out of their normal paths, and cam members 110 operatively connected to the lower rollers and adapted to force said rollers outwardly in said guides against the action of said springs when the sheets are returned to their normal paths.

ALEXIS KOBINE.
